UNITED STATES PATENT OFFICE.

WILLIAM A. STEVENSON, OF NORTHAMPTON, MASSACHUSETTS.

FILTERING APPARATUS.

SPECIFICATION forming part of Letters Patent No. 651,675, dated June 12, 1900.

Application filed April 20, 1898. Renewed March 17, 1900. Serial No. 9,108. (No model.)

To all whom it may concern:

Be it known that I, WILLIAM A. STEVENSON, a citizen of the United States of America, residing at Northampton, (Florence,) in the county of Hampshire and State of Massachusetts, have invented a certain new and useful Improvement in Filtering Apparatus, of which the following is a description, reference being had to the accompanying drawings, wherein—

Figure 1 is a plan view of the filtering apparatus, including the filter-bed. Fig. 2 is a view in sectional elevation on the plane denoted by the dotted line $x\ x$ of Fig. 1 looking in the direction denoted by the arrow overlying that line. Fig. 3 is a view in sectional elevation on the plane denoted by the dotted line $y\ y$ of Fig. 1 looking in the direction indicated by the arrow overlying that line.

The object of the improvement is the production of an apparatus for filtering liquids, notably water.

In the accompanying drawings the letters a and b respectively denote two tanks of similar capacity and construction. c denotes a tank intermediate of the two tanks just mentioned and the filter-bed d . The material of the filter-bed may well be sand. The water to be filtered comes through the intake-pipe e , feeding the unfiltered water alternately to tanks a and b .

The letter e' denotes that branch of the intake-pipe which feeds the unfiltered water to the tank a .

The letter f denotes a butterfly-valve controlling the admission of unfiltered water to tank a . The opening and closing movements of the butterfly-valve f are given through intermediate mechanism by the float g appurtenant to tank a . In the figures of the drawings the parts of the mechanism are shown in the adjustment they have when the float g has closed the butterfly-valve f and is at rest at the top of its play.

Suppose the float g to be at the bottom of its vertical play, with the inlet-valve f just opened. Then the incoming of the unfiltered water into tank a causes the float g to rise.

The letter g^2 denotes adjustable stops on the rod g' appurtenant to float g . The letter h' denotes an eye-block carried on the lever h , with pivotal attachment between the two, in

the eye of which eye-block the float-rod g' has vertical play. When the lowermost of the adjustable-stops g^2 strikes the eye-block h' , it will thereafter in its upward movement carry the lever h with it, giving, through shaft i , a corresponding rotary movement to pulley k . The pulley k has chain-belt connection through chain l , which is rather loose, so as to permit some lost motion with pulley m , which in the motion just described carries with it the weighted lever n in the same direction, which lever in that travel, passing the vertical, falls forward by gravity in the same direction of travel and in that fall closes the valve f and shuts off the inflow of unfiltered water to the tank a . The downward motion of float g from the top of its play begins, of course, with the opening of the outlet of this tank. The letter o denotes the outlet-valve of that outlet—a butterfly-valve. The opening of that valve is effected by mechanism which has its initial impulse given in the tank b , the construction and operation of which will be described hereinafter. When the outlet-valve o is thus opened, the inlet-valve f being meanwhile closed, it is a matter of course that the water in tank a falls and the float g falls with it. At the beginning of this falling motion of float g the lost motion of the adjustable stops g^2 with reference to eye-block h' is first taken up. Thereafter the further fall of float g pulls lever h downward, giving corresponding motion to pulley k , chain l , pulley m , and weighted lever n , and accordingly opening the inlet-valve f at the proper time, which is practically when the float g reaches the bottom of its play, at this point reestablishing the inflow of unfiltered water into tank a . In the before-described downward motion of the float g it also at the proper time, practically at the end of its downward play, closes the butterfly outlet-valve o by means now to be described. The letter p denotes a cam carried on the side of lever h , which, striking on the stud r , adjustably attached to crank-arm s , gives motion thereto and similar motion to pulley t , chain u , pulley v , and weighted lever w , which in this motion, being carried past the vertical, falls forward in the same direction and in that fall closes the outlet-valve o . At this time, the tank b being full of unfiltered water, the downward motion just described of crank-arm s opens the

outlet-valve o' of tank b through the medium of shaft z , pulley z' , chain z^2 , pulley z^3 , and weighted lever z^4 .

The opening and closing of the inlet-valve of tank a has now been described; also, the closing of its outlet-valve and the simultaneous opening of the outlet-valve of tank b .

Now to describe the opening of the outlet-valve of tank a . The operating mechanisms in the tanks a and b are duplicates of each other. The opening of the outlet-valve of tank a is accomplished by float a' at the closing of its downward movement through the medium of lever b' , (corresponding to h .) cam b^2 , (corresponding to p .) stud b^3 , (corresponding to r .) crank-arm b^4 , (corresponding to s .) shaft z , pulley t , chain u , pulley v , and weighted lever w . This opening of the outlet-valve of tank a is simultaneous with the closing of outlet-valve of tank b through mechanism already described.

In tank b the letter l' denotes that branch of the intake-pipe which feeds the unfiltered water to tank b . The letter a^3 denotes the float-rod of float a' . The letter a^3 denotes the adjustable stops on that rod. The letter a^4 denotes the eye-block, swiveled or pivoted to the lever b' . The letter m' denotes the shaft of the lever last mentioned, (corresponding to shaft i .) The letter m^2 denotes the pulley on the shaft last mentioned, (corresponding to pulley k .) The letter m^3 denotes the chain belt (corresponding to chain l) from pulley m^2 to pulley m^4 , (corresponding to pulley m .) The letter n' denotes a weighted lever, (corresponding to weighted lever n .)

The opening and closing of the inlet-valve c' of tank b is accomplished by mechanism contained within the tank b , which in construction and operation is a duplicate of that already described for the opening and closing of the inlet-valve of tank a , it being understood that in general one tank is being filled while the other is being emptied, and vice versa; but the inlet-pipe (and connections) of each of the tanks a and b is larger than the outlet-pipe (and connections) of the same tank, so that each tank is practically filled in less time than it is emptied, with the result that after the tank is once filled it stands filled for a substantial interval before the emptying process begins, a result which is a distinct utility in treating the water with alum or other suitable reagent preparatory to the passage of the water through the filter-bed. This utility concerns not only the efficiency of the reagent, but also concerns economy in the use and expenditure thereof.

The reagent which perhaps is the best one to use for all ordinary purposes is alum in solution. The alum in solution may be fed into the pipes which deliver the water into the tanks through pipes d' .

The water from the tanks a and b is delivered into the intermediate tank c , whence it passes through pipes d^2 to and upon the filter-bed d . After it has passed through the

filter-bed it is filtered, and the filtering process with which this apparatus deals is completed.

I claim as my improvement—

1. In combination, two tanks, an inlet for each tank, an outlet for each tank of less capacity than the said inlet of that tank, valves in said inlets and outlets, a float for each tank, and mechanism intermediate of said floats and said inlet and outlet valves adapted to cause the movements of the floats to automatically operate said valves—those of one tank alternately with those of the other tank—all substantially as described and for the purposes set forth. 75

2. In combination, a tank having an inlet-valve, the float in and for that tank, the float-rod of that float, the lever adapted to be operated—with some lost motion—by that float-rod, the pulley adapted to be operated by that lever, the chain from that pulley adapted to operate—with some lost motion—a second pulley, that second pulley adapted to operate 85 the weighted lever, and the weighted lever adapted to operate in opening and closing said inlet-valve, all substantially as described and for the purposes set forth. 90

3. In combination, a tank having an outlet-valve, the float in and for that tank, the float-rod of that float, the lever adapted to be operated—with some lost motion—by that float-rod, the cam on that lever, the crank-arm operated by that cam, the pulley operated by 100 that crank-arm, the chain operated—with some lost motion—by that pulley, the pulley operated by that chain, the weighted lever operated by the pulley last mentioned, and the outlet-valve adapted to be operated by 105 the said weighted lever, all substantially as described and for the purposes set forth. 95

4. In combination, a tank having an outlet-valve, the float in and for that tank, the float-rod of that float, the lever adapted to be operated—with some lost motion—by that float-rod, the cam on that lever, the crank-arm operated by that cam, the pulley operated by 110 that crank-arm, the chain operated—with some lost motion—by that pulley, the pulley operated by that chain, the weighted lever operated by the pulley last mentioned, the 115 said outlet-valve adapted to be operated by said weighted lever, a second tank, the outlet-valve of and for said second tank, the shaft of said crank-arm, the pulley fixed upon said shaft within said second tank, the chain operated—with some lost motion—by the pulley last mentioned, the pulley operated by the chain last mentioned, and the weighted 120 lever operated by the pulley last mentioned and itself adapted to operate the said outlet-valve of said second tank, all substantially as described and for the purposes set forth. 125
